UNITED STATES PATENT OFFICE.

CHARLES M. SHERWOOD, OF BROOKLYN, NEW YORK, ASSIGNOR OF ONE-HALF TO
ANTHONY C. LOPEZ, OF NEW YORK, N. Y.

SAFETY PIN.

1,408,538.

Specification of Letters Patent.

Patented Mar. 7, 1922.

Application filed June 10, 1921. Serial No. 476,454.

To all whom it may concern:

Be it known that I, CHARLES M. SHERWOOD, a citizen of the United States, and resident of the borough of Brooklyn, county of 5 Kings, city and State of New York, have invented certain new and useful Improvements in Safety Pins, of which the following is a specification.

This invention relates to improvements in 10 safety pins, and has for its object to provide a simple, inexpensive, and efficient locking device for preventing accidental disengagement of the pin tongue from the keeper member of the pin. To the foregoing and other 15 ends, which will hereinafter appear, the invention consists in the features of construction, and the arrangements and combinations of parts, set forth in the following description and particularly pointed out in the appended claims.

In the drawing:

Figure 1 is a side elevation of a safety pin provided with a locking device embodying the invention;

Fig. 2 a side elevation showing the opposite side of the pin from that illustrated in Fig. 1; and

Fig. 3 a sectional view taken on the line 3-3 of Fig. 1.

The safety pin proper may be of any suitable or known construction. As illustrated, it comprises a piece of resilient wire bent to form a keeper-carrying member 10 and a pin-tongue member 11 connected together 35 at one end by an integral coil portion 12 which forms the usual spring-hinge connection between said members. One arm of the usual U-shaped keeper 13 is rigidly held to the free end of member 10 and the other arm 40 14 thereof is provided as usual with an inwardly facing channel adapted to receive the free pointed end of the tongue member 11 in the well known manner, as indicated in Figs. 1 and 2. The parts heretofore described are of well known construction.

In order to prevent accidental disengagement of the tongue member 11 from the keeper I provide a locking member or safety device which is adapted to prevent flexing, 50 bending, or swinging of the tongue member either toward or from the keeper-carrying member 10, and thus prevent the pointed end of the tongue member from being pressed in-

wardly below the side walls of the channeled arm 14 of the keeper or from being pulled 55 from the channel in said arm 14 by outward flexing or bending of the tongue member under a severe pulling strain.

The improved safety device or latch is formed in its entirety of a single narrow 60 strip of sheet metal doubled upon itself to form two opposed and slightly diverging arms 15 and 16 connected together at their converging ends by an integral tubular pivot portion or sleeve 17. The keeper-carrying 65 member 10 of the safety pin extends through the tubular portion or sleeve 17 of the locking device, said sleeve having a snug rotating and sliding engagement with member 10 to permit the locking device to be swung 70 about member 10 and shifted longitudinally of said member.

The free end of the arm 15 is bent or curved upwardly and laterally and then downwardly to form a slightly resilient hook 75 18 adapted to be engaged over the tongue member 11 to resist outward pulling strains. The downwardly turned end edge of the hook is preferably doubled upon itself to form a stiffening flange 19 for reinforcing 80 said end edge and to provide a rounded nose 20. The end of arm 16 is bent laterally toward arm 15 to form a shelf or abutment 21 below hook 18 adapted to resist pressure of tongue member 11 toward member 10. 85 A narrow tongue or lug 22 is formed on the inner end of shelf 21 intermediate the side edges of said shelf. Lug 22 extends through a slot 23 in arm 15 and is bent against the outer side of said arm to prevent 90 separation of the divergent ends of the arms 15 and 16. The shoulders formed by the inner end of shelf 21 at opposite sides of lug 22 abut against the inner side of arm 15 and prevent movement of the divergent ends 95 of arms 15 and 16 toward each other. Shelf 21 is preferably formed to provide a rounded edge or nose 25 directly under nose 20 of hook 18 and is bowed downwardly to form a channel curved on the same arc 100 as the surface of the tongue member 11, as shown in Fig. 3. Hook 18 is also preferably curved on the same arc as the tongue member 11, and noses 20 and 25 are spaced apart a distance less than the diameter of tongue 105 member 11 so as to form a restricted throat

or slot 26 through which the tongue member is adapted to pass only after flexing of the resilient hook away from shelf 21.

The operation of the device is as follows:

- 5 The free end of the locking device being disengaged from member 11, and member 11 being disengaged from keeper 13, the tongue member is passed through the pieces of fabric or the like to be pinned together and the 10 tongue member is then engaged with the keeper in the usual way. The free end of the locking device is then swung toward the tongue member and pressure is exerted thereon to force the tongue member 15 through the throat 26, the rounded edges 20 and 25 facilitating this action as the locking device is pressed against the tongue member. When it is desired to remove the pin, pressure or pull is exerted laterally on 20 the locking device to snap the same off of the tongue member, whereupon the safety pin may be removed in the usual way.

It will be obvious that various changes may be made in the construction of the improved safety lock without departing from the invention. In Fig. 2 the preferred manner of attaching the pin to fabrics is shown, but it will be obvious that it is not essential that this manner of attaching the 25 pin be employed. In Fig. 2 the tongue member is shown passed four times through two plies of fabric 27 and 28 and the safety lock is shown engaged with the tongue member of the pin intermediate the second 30 and third points of penetration.

An important feature of the invention consists in the provision of a safety locking device adapted to be adjusted longitudinally of the pin so as to permit locking the tongue 40 and keeper-carrying members together at any convenient point. A further highly important feature of the invention consists in providing a locking device adapted to separably connect the keeper-carrying member 45 and the tongue member of the pin, said device being so constructed as to resist compression strains as well as pulling strains on the members.

What I claim is:

- 50 1. The combination with a safety pin having a member carrying a tongue-keeper and a pin tongue member connected with said keeper-carrying member, of an auxiliary safety device pivotally and slidably held to the keeper-carrying member and provided at its free end with spring clasping means for gripping the tongue member and holding the tongue member against movement both toward and from the keeper-carrying 55 member, said spring clasping means having a restricted entrance throat at one side thereof to permit engagement and disengagement of the clasping means with the tongue member while said tongue member is engaged in 60 the keeper solely by pressure on said device 65

transversely a plane intersecting the tongue and keeper-carrying members of the pin.

2. The combination with a safety pin having a tongue-keeper and pin-tongue and keeper-carrying members, of an auxiliary 70 safety device attached to the keeper-carrying member and provided with means operable by pressure transversely of a plane intersecting the tongue and keeper-carrying members for releasably engaging the tongue 75 member after the same is engaged in the keeper and positively holding said tongue member against movement toward and from the keeper-carrying member.

3. A pin-fastener comprising a keeper-carrying member and a pin-tongue member connected together at one end, a keeper held to the other end of the keeper-carrying member adapted to receive the free end of the pin-tongue member, and a metal brace 80 having a tubular portion at one end through which the keeper-carrying member loosely extends and provided at its other end with a hook-portion adapted to engage over the pin-tongue member and a shelf-like portion 85 intermediate the hook-portion and tubular portion adapted to engage under the pin-tongue member.

4. An auxiliary safety attachment for safety pins comprising a single strip of sheet 90 metal doubled upon itself and crimped adjacent the point of fold to form a tubular pivot portion adapted to receive the keeper-carrying member of a safety-pin and having its ends bent at an angle to the body 95 portion of the device one above the other to form a clasp adapted to receive the tongue member of the safety-pin.

5. A pin fastener comprising a keeper rod, a keeper held to one end of said rod, a pin 105 tongue connected at one end with said keeper rod and having a pointed end adapted to be engaged in said keeper, and a safety device pivotally held to the keeper rod intermediate the ends of said rod to swing laterally relatively to the rod, said device being provided at its free end with a hook adapted to be sprung over the pin tongue to resist movement thereof away from the keeper rod and being also provided with an abutment adjacent said hook and adapted to engage the pin tongue to resist movement of the tongue toward the keeper rod.

6. Means for bracing the members of a safety pin comprising a single strip of sheet 110 metal doubled upon itself to form a pair of divergent arms connected at their converging ends by a sleeve-like portion adapted to receive the keeper-carrying member of the pin, the other end of one arm being 115 bent to form a hook and the other end of the remaining arm being bent laterally to form an abutment spaced from and facing the concave side of said hook, said laterally bent portion being secured to the hook- 120

carrying arm, and the space between the laterally bent portion and said hook forming a socket for receiving the tongue member of the pin.

- 5 7. A pin fastener comprising a keeper-carrying member and a pin-tongue member connected at one end by a spring coil, a keeper rigidly held to the other end of the keeper-carrying member adapted to receive
- 10 the pointed free end of the tongue member, a laterally swinging brace pivotally held at one end to the keeper-carrying member provided at its free end with an integral resili-

ent hook portion the concave side of which faces the pivoted end of the brace, said brace 15 being provided with a laterally extending abutment under the concave side of the hook portion thereof, said hook portion and abutment forming spring means for clasping the tongue member of the pin in such 20 manner as to resist movement thereof either toward or from the keeper-carrying member.

In testimony whereof I hereunto affix my signature.

CHARLES M. SHERWOOD.
